UNITED STATES PATENT OFFICE.

SAMUEL JAMES DONNELLY, OF AUGUSTA, GEORGIA.

DESIGN FOR A VIOLIN-BRIDGE.

SPECIFICATION forming part of Design No. 33,814, dated January 1, 1901.

Application filed December 5, 1900. Serial No. 33,843. Term of patent 14 years.

To all whom it may concern:

Be it known that I, SAMUEL JAMES DONNELLY, a citizen of the United States, and a resident of Augusta, in the county of Richmond and State of Georgia, have invented and produced a new and original Design for a Violin-Bridge, of which the following is a specification, reference being had to the accompanying drawing, forming a part thereof, in which is represented a perspective view of a violin-bridge embodying the features of my design.

The leading feature of the design consists in the arched hook-shaped upper or head section of the bridge, which head-section at its left hand is connected by a shank with the base-section of the bridge.

The minor features of the design consist in

the curved formation of the shank and the curved recess in the right-hand side of the bridge, which recess serves in part to form the shank and separates the right-hand portion of the head-section from the corresponding portion of the base-section.

Having thus described my invention, I claim as new and desire to secure by Letters Patent—

The design for a violin-bridge herein shown and described.

In testimony whereof I have signed my name to this specification in the presence of two subscribing witnesses.

SAMUEL JAMES DONNELLY.

Witnesses:

D. G. FOGARTY,
GEO. B. POURNELLE.
